CLAMPING TOOL FOR APPLYING AUTOMOBILE
TIRE CHAINS

Michael B. Kendis, 4539 Roanoke Parkway,
Kansas City, Mo.

Filed Sept. 19, 1960, Ser. No. 62,183

Term of patent 14 years

(Cl. D54—13)

FIG. 1 is a front perspective view of a clamping tool for applying automobile tire chains, showing my new design;

FIG. 2 is a rear elevational view thereof;

FIG. 3 is a sectional view thereof taken on line 3—3 of FIG. 2;

FIG. 4 is a sectional view thereof taken on line 4—4 of FIG. 2; and

FIG. 5 is a sectional view of the clamping tool for

applying automobile tire chains, taken on line 5—5 of FIG. 2.

I claim:

The ornamental design for a clamping tool for applying automobile tire chains, as shown.
